DESIGN FOR A BATTERY

Clifford Brooks Stevens, Milwaukee, Wis., assignor to Solar Corporation, Milwaukee, Wis., a corporation of Delaware

Application July 9, 1945, Serial No. 120,573

Term of patent 14 years

(Cl. D26—6)

To all whom it may concern:

Be it known that I, Clifford Brooks Stevens, a citizen of the United States, residing at Milwaukee, in the county of Milwaukee and State of Wisconsin, have invented a new, original, and ornamental Design for a Battery, of which the following is a specification, reference being had to the accompanying drawing, forming a part thereof, in which

Fig. 1 is an elevation of one side of the battery showing my new design.

Fig. 2 is an elevation of one end of the battery.
Fig. 3 is an elevation of the other side of the battery.

Fig. 4 is an elevation of the other end of the battery.

I claim:

The ornamental design for a battery, as shown.

CLIFFORD BROOKS STEVENS.
